OTHER PUBLICATIONS

USPTO Notice of Allowance dated Feb. 24, 2016 in related technology U.S. Appl. No. 29/525,820.

Primary Examiner — Michael A. Pratt*Assistant Examiner* — Michelle E Wilson(74) *Attorney, Agent, or Firm* — Morgan, Lewis & Bockius LLP**(57) CLAIM**

We claim the ornamental design for a washing machine, as shown and described.

DESCRIPTION

The FIGURE provides a perspective view of a washing machine showing our new design.

The broken lines shown in the drawing illustrate unclaimed portions of the washing machine and form no part of the claimed design.
